INVENTOR
CHARLES A. FRENCH.

BY William W. French
ATTORNEY.

UNITED STATES PATENT OFFICE.

CHARLES ALBERT FRENCH, OF MADISON, WISCONSIN.

DOOR STOP AND HOLDER.

1,416,276.

Specification of Letters Patent. Patented May 16, 1922.

Application filed July 12, 1920. Serial No. 395,755.

To all whom it may concern:

Be it known that I, CHARLES ALBERT FRENCH, a citizen of the United States, residing at Madison, in the county of Dane and 5 State of Wisconsin, have invented certain new and useful Improvements in Door Stops and Holders, of which the following is a specification.

My invention relates to door holders and 10 locks combined and the objects of my invention are, first, to provide a means for holding doors open; second, to provide a means for converting the holder when the doors are closed into a positive bar and lock, 15 thus preventing opening the door from the outside.

I attain the above and other objects which 20 will be apparent upon examination of the following complete specification and accompanying drawings in which—

Fig. 1, is a side elevation of the members secured to the head jamb; Fig. 2, is a vertical section through Figs. 1 and 3, on line A—B; Fig. 3, is a plan of Fig. 1; Fig. 25 4, is a plan of the entire device as attached to a door and Fig. 5, is a perspective view of the device attached to a door in closed position, showing means of locking.

Similar numerals refer to corresponding 30 parts throughout the several views.

The jamb plate 1, is provided with screw holes 2, for attaching to the head jamb of a door frame. A circular recess 3, is located in the top thereof, and a similar recess 4, is 35 formed on the lower side, leaving a circular flange 5, between the two. A race or sleeve 6, having a circular plate 7, on the upper side approximate the front end thereof, is pivotally secured in the lower recess 4, of the plate 1, by a rivet 8. Said rivet 8, passes 40 through the hole 9, and washer 10, and is headed over the said washer. A plate 11, is disposed on the door 12, and secured to the same by bolts or screws 13. Said plate 45 11, is provided with outwardly projecting ears 14, and a rod 15, made preferably of steel channel, is pivotally connected within the said ears 14, by a rivet 16, which is drilled near its lower end to receive a cotter 50 pin 17.

The said rod 15, passes backward from the plate 11, and is slidably mounted in the sleeve 6, which is provided with two depending lugs 18. Between said lugs, a latch 55 19, is loosely mounted on pin 20. The rear end of said latch being enlarged to form

a weight back of the pin, and the front end is reduced forming a catch 21, adapted to seat in the hole 22, adjacent the rear end of the rod 15, see Fig. 4. A stop plate 23, is 60 secured over the rear end of the rod 15, by rivets 24, as shown or any other suitable means and is provided with an eye 25, integral therewith and adapted to engage a hook 26. Said hook 26, being attached to 65 the wall inside of the building. The latch 19, before mentioned is drilled near the front end for attaching a chain or cord, for releasing the catch 21, from engagement with the aperture 22, in the rod 15, thus 70 allowing the door to be closed.

It is obvious that when the door 12, is opened sufficiently the rod 15, will be drawn outward until the stop plate 23, abuts the end of the sleeve 6, which brings the hole 75 22, in the rod 15, directly above the catch 21, on the latch 19, and the rear end of the latch 19, being heavier the catch will enter and remain in engagement with the aperture 22, until released by a slight downward 80 pull on the chain 27.

When the doors are in closed position, see Figs. 4 and 5, the rear end of the rod approaches so near the wall that the hook 26, 85 may be connected to the eye 25, and the rod will act as a bar lock, preventing the door from being forced open from the outside.

Having thus described my invention I claim as new, the following:

1. In a door holder, a door plate provided with two outwardly extending ears, means for attaching said plate to a door, a jamb plate adapted to be secured to the head jamb of a door frame and provided with a circular recess in the top portion 90 thereof and a similar recess in the bottom portion, a race or sleeve provided with a circular plate on the upper side approximate the front end thereof, said circular plate revolvably disposed within the lower recess 95 in said jamb plate, an aperture located in the lower side of said sleeve, two depending lugs integral with said sleeve and disposed on either side of said aperture, a latch pivotally secured between the lugs aforesaid, 100 the front end of said latch adapted to pass through the aperture in said sleeve, a rod secured between the outwardly extending ears of the aforementioned door plate and slidably disposed in the race or sleeve, an aperture formed in said rod adapted to register 110 with the aperture in said race when the door

is in open position, a stop plate secured to the rear end of said rod adapted to stop the travel of said rod through said sleeve and to allow the catch to seat in the aperture in the rod.

2. In a door holder, a door plate provided with two outwardly extending ears, means for attaching said plate to a door, a jamb plate adapted to be secured to the head jamb of a door frame and provided with a circular recess in the top portion thereof and a similar recess in the bottom portion, a race or sleeve provided with a circular plate on the upper side approximate the front end thereof, said circular plate revolvably mounted in the bottom circular recess of said jamb plate, an aperture in the bottom portion of said sleeve, two depending lugs integral with said sleeve and disposed on either side of said aperture, a latch pivotally secured between the lugs aforesaid and having its rear end enlarged to form a weight and its front end reduced to form a catch adapted to pass through the aperture in said sleeve, a rod pivotally secured between the outwardly extending ears of said door plate and slidably disposed in the race or sleeve, an aperture in said rod adapted to register with the aperture in said sleeve and to receive the catch aforesaid, a stop plate secured to the rear end of said rod and comprising a tang secured to said bar, an eye formed on the end of said tang, a hook adapted to be fastened to the wall inside of a building and to engage the eye for the purpose described.

3. In a door holder, a door plate provided with two outwardly extending ears, means for attaching said plate to a door, a jamb

plate adapted to be secured to the head jamb of a door frame, said jamb plate provided with a circular recess in the top portion thereof and a similar recess in the bottom portion, a race or sleeve provided with a circular plate on the upper side approximate the front end thereof, said circular plate revolvably mounted in the bottom circular recess of said jamb plate, an aperture in the lower side of said sleeve, two depending lugs integral with the lower side of said sleeve and disposed on either side of said aperture, a latch pivotally secured between the lugs aforesaid and having its rear end enlarged to form a weight and its front end reduced to form a catch adapted to pass through the aperture in the sleeve, a means for operating said catch, a channel bar having its front end pivotally secured between the outwardly extending ears of said door plate and its rear end slidably disposed in said sleeve, an aperture in said bar adapted to register with the aperture in the sleeve and to receive the catch aforesaid, a stop plate secured to the end of said channel bar adapted to stop the travel of said bar and to allow the catch to enter the aperture in the bar when door is opened, an eye integral with said stop plate, means secured to the inside wall of a building adapted to engage the eye aforementioned for the purpose described.

In testimony whereof I affix my signature in the presence of two subscribing witnesses.

CHARLES ALBERT FRENCH.
